United States Patent Office

Des. 188,841
Patented Sept. 20, 1960

188,841

SHOPPING CART

Martin Umanoff, Huntington, N.Y., assignor of an undivided part each to John H. Moses, New York, Vincent S. Andrews, Manhasset, and Arthur B. Modell, Brooklyn, N.Y., Robert Jay Leder, Stamford, Conn., Sydney Rubin, Great Neck, N.Y., and John P. Cleary, Glen Ridge, N.J.

Filed Mar. 21, 1960, Ser. No. 59,801

Term of patent 14 years

(Cl. D14—3)

I claim:

The ornamental design for a shopping cart, substantially as shown.
